SPEED CUP BALANCING MACHINE

Charles W. McKinley, Lucian B. Smith, and Clarence E. Dinsmore, Flint, Mich., assignors to General Motors Corporation, Detroit, Mich., a corporation of Delaware

Application November 1, 1935, Serial No. 47,750

10 Claims. (Cl. 73—51)

This invention relates to a process and a machine for balancing a freely swinging element and has been designed particularly for balancing the speed cup of a magnetic measuring instrument.

The object of the invention is to effect a more accurate balancing of the speed cup, to balance the cup in a way which shall be permanent, to save time in the process of balancing, and to avoid cut and try procedure.

10 A further object, and one useful not only in this machine but elsewhere, is the provision of a novel form of oscillating bearing to reduce friction at the bearing support.

15 Other objects and advantages will be understood from the following description.

The invention is illustrated in the accompanying drawings in which:

Fig. 1 is a top plan view of the machine.

Fig. 2 is a perspective of a detail.

20 Fig. 3 is a view partly in elevation and partly in section substantially as seen from line 3—3 of Fig. 1.

Fig. 4 is an enlarged partial top plan view.

Fig. 5 is a section on line 5—5 of Fig. 4.

25 Fig. 6 is a disassembled perspective of a part of the machine.

Fig. 7 is a sectional view on line 7—7 of Fig. 3.

Fig. 8 is a sectional view of a part of the machine, the view being at right angles to that of Fig. 3.

30 Figs. 9a, 9b, 9c are diagrams showing the steps in the operation.

Referring by reference characters to the drawings, numeral 11 is a base shown on a platform 10 for supporting the various parts of the machine. To the base are secured by fastening means 13 longitudinally disposed undercut guides 15 for sliding engagement with the support 17 upon the upper concave surface of which rests an electric motor (see Figure 7). The fore and aft movement of the support 17 similarly carries the electric motor 19. Fastening means 21 secure the motor in position. Rigid with support 17 is an end wall 23, and to the adjacent end of base 11 is fastened as by screws 25 an abutment 27 between which and wall 23 are coil springs 29 operative to move the support and motor away from abutment 27. To the wall 27 is pivoted at 31 a lever arm 33, and a link 35 is pivoted to lever 33 at 37 and to wall 23 at 39. The pivots are positioned as shown so that when the lever is in the position of Fig. 3 the spring is compressed but the pivot 37 is in alignment with pivots 31 and 39, whereby the spring is incapable of moving the motor. When the lever 33 is raised and rotated,

pivot 37 moves up and out of alignment with pivots 31 and 39 and the springs 29 function to move the motor toward the other end of the machine assisting the lever in so doing.

To the motor 19 there is secured by fastening means 41 a casting 43. This casting has a projection 45 of tubular form which supports a head 47 slidably secured thereto as at 48. An end milling cutter 49 is located within the tubular projection 45. At 51 on casting 43 is fulcrumed a 10 disc 53. The disc has an arcuate slot 55 through which the projection 45 extends, the slot permitting the rotation of the disc about pin 51. There is an operating handle 57 secured to the disc by fastening means 59. The disc has an axial pin 15 61 projecting from its face. The disc is provided with a cam surface 63 which surface contacts with the protruding surface or portion 65 at the rear end of head 47. A spring 67 is located between a shoulder 69 of the head 47 and a spacer 20 71 which surrounds the casting 43 and engages said casting whereby the spacer becomes a fixed abutment for the spring.

A corner block is seen at 73 fastened to base 11 in any convenient way. A lever arm 77 is pivoted at 79 to this block. A spring 81 anchored at 83 and attached to the lever at 85 biases the lever to the position shown by Fig. 1. The lever has a tangential arm 87 to one side of which are secured by a screw 89 flat springs 91 adapted in one position of the arm to engage a stop 93 projecting from the block. A cross head 95 is normally held in spaced relation to the tangential arm 87 by pins 97 secured thereto, projecting through the arm and pressed forward by the springs 91 as best shown in Fig. 5. Between the pins a punch 99 projects from the arm 87, being fixedly held by a screw 101. The punch extends through an opening 103 in cross head 95.

Corner block 73 has an extension at 105 carrying an arcuate die 107. This die is intended to be engaged by the inner bottom wall of a speed cup of a speedometer, this wall being shown in Figs. 4 and 5 where it is designated by numeral 109. The die 107 has a hole 111 for the passage of the 45 punch 99 after the punch has made an opening in wall 109, this being accomplished by rotating the lever 77 as will be understood from Fig. 1. Passing through the extension 105 is a thrust bearing 113 to engage the end of the speed cup 50 spindle 115. This thrust bearing is held yielding against its stop 117 by a spring 119 as is shown by Fig. 3.

Two posts 121 and 123 support a cross bar 125 having spaced vertical walls 127 to which are 55

secured by fastening means 129 flat plates of resilient steel the upper edges of which appear in Fig. 1 and are marked by numeral 131. These plates are free to vibrate toward and from each other. The plates extend to the region of the die 107 and the head 47 and to their ends are secured by fastening means 133 spool supports 135, the spool supports having opposed lugs 131 carrying pins 139 the adjacent ends of which are tapered for the support of spool-like members 141. The parts are dimensioned so that the speed cup spindle when supported on these spools is axially aligned with thrust bearing 113 and the speed cup itself may engage the die 107, its outer wall surrounding the die as shown in Fig. 4. Secured to cross bar 125 by fastening means 143 is a synchronous clock motor 145 the details of which need not be described. The shaft 147 driven by the motor carries a plural face cam 149 engaging abutments 151 secured to the resilient plates 131. A box-shaped cover 153 is secured by screws 153 to the cross bar 125. By this motor cam expedient the two supporting spools are being moved alternately toward and from each other. In this way the speed cup is mounted on movable supports which ensure free rotation. The support is sure to cause the cup to rotate to an extent such as to bring the excess weight at the bottom of the vertical axis of the cup. It is this point of the cup which is to be engaged by the end cutter 49 when the lever 33 is rotated and the head 47 moved to clamp the bottom wall of the cup between itself and the die 107. The punch 99 is so located that the hole it punches in the said bottom wall is near the end of the horizontal diameter.

A vacuum cleaner device designated by numeral 155 and provided with a trough 157 may be positioned as shown and is used to withdraw the chips produced by the cutter as it removes metal from the speed cup. No invention per se is being claimed for this cleaner and it need not be further described.

The operation is as follows: The spindle of the speed cup is placed with its ends on the spools 141, one end being in contact with the thrust bearing 113. While so mounting the cup the arm 33 is swung back so that the motor 19 is withdrawn and the head 47 is spaced from the die 107. Arm or lever 77 is being held in inoperative position by its spring 81. The operation of the synchronous motor moves the spools simultaneously toward and from each other, whereby the speed cup is free to rotate and will rotate so that its heavy part will assume a position in the lower part of its vertical diameter. Lever 77 is then rotated until cross head 95 engages the bottom wall of the cup 109 and a further movement causes the punch to make a hole in the cup at the horizontal diameter, the punch entering hole 111 in the die, this movement causing the pins 97 to deflect the springs 91 which operate to release the punching mechanism after the hole has been made. The punch is then swung back to its inoperative position by the spring 81. The hole punched in the cup disturbs its balance and it swings to a new position of rest wherein the hole moves from the horizontal diameter upwardly. The new position again brings the unbalance weight into the lower part of the vertical diameter, the vibrating supporting spools being relied on to ensure the free swinging of the cup.

When the cup has assumed its new position, the lever arm 33 is rocked to permit the springs 29 to

push forward the motor together with the head 47, the disc 53 and the cutter assembly so that the cup bottom is gripped firmly between the said head and the die 107. In so swinging the lever arm 33 a conventional mercury switch carried thereby and indicated by numeral 159 closes a circuit through suitable wires 161, a source of energy (not shown) and both the motor 19 for operating the cutter and the vacuum cleaner motor for the purpose of cutting out metal and removing the chips.

The depth of metal to be cut is measured by the arc of rotation of the speed cup from the original position of rest to its position of rest assumed after the hole is punched. That depth is determined by a rotation of the arm 57 of the disc 53 until its pointer registers with the punched out hole in the disc. The cam face 63 operates to attain this result. The spring 67 between the shoulder 69 and the spacer 71 normally holds the end of the head somewhat beyond the end of the cutter, the fastening means 48 permitting a limited movement between the part 45 and the head 47. When the device is in use this movement of the head produces a clearance between the disc 53 and the cooperating surface 65. When the springs 29 push the assembly forward the head 47 is stopped against the speed cup and the pressure from the springs 29 overcomes the spring 67 and the head is moved back relatively to the extension sleeve 45 so that the end mill is free to work on the speed cup. In so moving back, its face 65 engages the cam face 63 of the disc, thus limiting the relative movement. Progressively thinner regions of cam surface 63 contact face 65 as the disc is rotated in the act of bringing its pointer 61 into registration with the punched out hole. As these thinner portions are brought opposite the face 65, the head is able to slide back further to permit an added projection of the mill. In this way the degree of rotation of arms 57 determines the degree of cutting and does so in proportion to the extent to which the disc has rotated after the hole was punched.

The theory may be made clearer by reference to the diagram. Fig. 9a shows the condition of the speed cup before the first operation. A degree of unbalance has caused the cup to rotate freely so that the unbalance marked W_2 assumes the position shown. The hole W is then punched out as in Fig. 9b and, as described above, in the horizontal axis. This is equivalent to adding a mass W_1 equal to W in the position shown. The disc, after rotating to its new position, then may be balanced by removing a mass W_3 from the bottom of the vertical diameter. The amount to be removed may be determined by the expression where

$$W_3 = W \frac{1}{\cos b} \quad 60$$

In this equation, where W_3 is the amount of material to be removed, W is the mass removed by the punch, angle b is the complement of angle a , the latter being the angle through which the punched cup rotated after the hole was punched. The cam face on the disc is so shaped that when the disc is rotated to an extent such that the pointer registers with the punched hole, the cutter will remove the required amount of material.

The machine thus does away with all cut and try steps of balancing, is extremely accurate in its results, and saves much time.

We claim:

1. The process of giving static balance to an

- unbalanced element consisting in mounting said element for free rotation to localize its unbalanced weight in its vertical axis, removing material from one side of said axis, permitting the 5 element to swing to a new position of rest and removing material to balance the element, the depth of removal being determined by the mass of material first removed and the extent of rotation resulting from such first removal.
- 10 2. The process of balancing an out of balance freely rotatable element comprising removing material from a position in its horizontal axis at one side of its vertical axis, permitting said element to rotate after said removal of material and 15 subsequently cutting material from the bottom of the vertical axis, the depth of cutting being determined by the mass of material first removed and by the angle of rotation of the element after said first removal.
- 20 3. The process of giving an unbalanced element a static balance consisting in mounting the element for free rotation whereby its out of balance weight lies in the vertical axis, removing material from a region in the horizontal axis 25 at a given radial distance from the center of rotation, permitting the element to rotate to a new position of rest, removing material at the same radial distance in the vertical axis, the mass of material last removed being dependent upon 30 the mass first removed and the arc of rotation subsequent to said first removal.
4. The invention defined by claim 3, said mass last removed being determined by the expression

$$35 W_3 = W \frac{1}{\cos b}$$

where W is the mass first removed, W_3 the mass to be finally removed, and b equals the complement of the angle through which the element rotates after the first removal.

- 40 5. In a machine to give static balance to an unbalanced element, means constituting a part of said machine to support said element for free rotation about a horizontal axis whereby its out of balance weight lies in its vertical axis, means 45 constituting a part of said machine positioned adjacent said first means and operable to punch a hole in said element at a given radial distance and on a horizontal axis whereby said element may rotate to a new position of rest, other means 50 constituting a part of said machine, positioned adjacent said first means and operable to cut material from the element in its vertical axis and at the same radial distance, and additional manually operable means movable to predeter-

mine the mass of material removed by the said other means to produce in said element a static balance.

6. In combination, first means to support a disc for free rotation about a horizontal axis, second means positioned adjacent said first means and operable to punch a hole in said disc at a certain radial distance in its horizontal axis whereby said disc may rotate about its axis to a new position of rest, third means adjacent said 10 first and second means and operable to cut material at the same radial distance from the disc's vertical axis, and a fourth means movable to an extent dependent upon the mass of material removed by the second means and by the rotation 15 of the disc subsequent thereto to determine the mass of material removed by the third means.

7. The invention defined by claim 6, said third means including a motor and end cutter operated thereby and manually operable means to 20 move said motor and cutter jointly into operative position.

8. The invention defined by claim 6, said third means including a motor and end cutter operated thereby and manually operable means to 25 move said motor and cutter jointly into operative position together with a switch actuated by the movement of said manually operable means to render said motor operable.

9. The invention defined by claim 6, said second means comprising a manually operable lever having an extension, a cross head, pins carried by said cross head and extending through said extension, yielding means on said extension and acting on said pins to space the cross head 35 and a punch secured to the extension and extending through the cross head.

10. The invention defined by claim 6, said third means comprising an axially movable electric motor having a shaft, an end cutter in axial alignment therewith and rotated thereby, sleeve means secured to the motor and surrounding the cutter, a hollow head slidably surrounding said sleeve and cutter, yielding means to project the end of said head along the sleeve and beyond the 45 cutter, spring means to project said motor and head into contact with the disc and to thereby overcome said yielding means to produce a reverse movement of the head and bring the cutter into operative position, and said fourth means 50 being operable to vary the limit of the reverse movement of said head.
